UNITED STATES PATENT OFFICE.

WILLIAM W. MOYER, OF LYKENS, PENNSYLVANIA.

WATER-MOTOR.

SPECIFICATION forming part of Letters Patent No. 609,692, dated August 23, 1898.

Application filed May 1, 1896. Serial No. 589,873. (No model.)

To all whom it may concern:

Be it known that I, WILLIAM W. MOYER, a citizen of the United States, residing at Lykens, in the county of Dauphin, State of Pennsylvania, have invented certain new and useful Improvements in Water-Motors; and I do hereby declare the following to be a full, clear, and exact description of the invention, such as will enable others skilled in the art to which it appertains to make and use the same.

My invention relates to washing-machine motors in general; and it has for its object to provide means and mechanism for rendering the machine automatic in every particular, so that the clothes may be contributed thereto, the mechanism set in operation, and the whole device left to itself to accomplish its work.

In the drawings forming a part of this specification and in which like symbols of reference indicate similar parts in the several views, Figure 1 is a perspective view of a washing-machine with operating mechanism attached. Fig. 2 is a vertical section of the water-motor employed by me, and Fig. 3 is a section on line 3 3 of Fig. 2.

Referring now to the drawings, *a* represents an ordinary washing-machine of inverted-tub shape and provided with a suitable number of supporting-legs *b*. The particular machine shown herein is provided with certain interior oscillating mechanism, to which motion is given through the medium of a beveled gear *c*, meshing with a similar gear *d*, journaled in suitable supports *e*, secured to the tub *a*. This gear *d* has pivoted to it a reciprocating rod *f*, to which is pivoted a lever *g*, pivoted to any suitable fulcrum, such as ears *h*, on the side of the tub *a*. The work end of the lever *g* is pivoted to the piston-rod *i* of a motor *j*, secured, preferably, to the under side of the body of the tub *a*.

The motor *j*, which is preferably operated by water-pressure, is more specifically shown in Figs. 2 and 3 of the drawings, in which *k* is the main cylinder, formed like the usual main cylinder of a steam-engine and provided with a piston-head comprising a disk *l*, of metal, arranged on the piston-rod *i*, above referred to, and having on each side thereof disks of packing *m* and *n*, respectively, each dished outwardly, as shown in Fig. 2 of the

drawings, in order that the pressure of water in the cylinder may operate to cause the packing to fit closely when acted upon thereby. 55

Washers *o* and *p* are clamped against the packing-disks *m* and *n* by means of clamp-nuts *q* and *r* in engagement with suitable threads on the extremity of the piston-rod *i*. 60

The cut-off slideway *s* within the water-chest *s'* is in this instance provided with two series of ports arranged side by side, the inlet-port of one series having communication with the inlet-port of the other series in order that they may simultaneously receive 65 water from the inlet-pipe *t*.

Separating the water-chest *s'* into two parts *u* and *v* is a vertical partition *w*, having one upper corner cut away adjacent the outlet-orifice *x* to allow discharge from both divisions through the same outlet. 70

The inlet-ports *y* and *z* communicate with the rearward and forward ends of the main cylinder *k*, respectively, water being directed into first one and then the other through the 75 medium of a cut-off *5*, which is reciprocated to cover the inlet-port *y* and outlet-port *z* and then the inlet-port and outlet-port *y*.

In order to reciprocate the cut-off *5*, its operating-rod *7* is connected, through the medium of a rock-lever *8*, Fig. 2, pivoted to a suitable fulcrum *9*, with the piston-rod *10* of the minor cylinder *11*, secured, preferably, to an upward projection *12* of the water-chest *s'*. The piston-rod *10* is provided with a piston-head *14*, having a construction similar to that of the piston *i* and for the same purpose. Water is contributed to the cylinder *11* through the medium of pipes *15* and *16*, leading from the ports *17* and *18*, respectively, in 90 the second division *u* of the slideway. These pipes *15* and *16* enter the minor cylinder through the heads thereof, and thus contribute water to move the piston *14* in accordance with the position of the cut-off *19* with respect to the ports *17* and *18*. 95

In order to operate the cut-off *19*, it is provided with a reciprocating rod *20*, extending freely through a collar *21*, attached securely to the piston *i*, said collar being arranged to 100 strike a spring-stop in its outward movement and to strike a second spring-stop in its inward movement (which said stops are arranged on the reciprocating rod *20*) to move

the rod 20 and contribute motion to the cut-off 19. These stops are formed by securing collars 22 and 23 to the rod 20, against the adjacent faces of which are arranged helical 5 springs 24 and 25 to receive direct engagement of the collar 21. The collars 22 and 23 are secured in place through the medium of set-screws in order that they may be adjusted to give motion to the rod 20 at the proper 10 time.

The operation of the device is as follows: A hose or other connection is made with the inlet-pipe t , when water rushes through inlet-port 6 and outlet-port z and causes piston-rod 15 i to move inwardly and the collar 21 to strike the spring 24. This moves the cut-off 19 to cover outlet-port 17, causing piston-rod 10 of minor cylinder 11 to move outwardly, which moves cut-off 5 to cover inlet-port y and contribute pressure to the inner end of the piston of rod i , causing it to move outwardly. Just before the termination of the outward movement the collar 21 on rod i strikes the 20 spring 25, causing the cut-off 19 to shift its position and cover outlet-port 18, when the piston of the minor cylinder will be thrown inwardly, drawing the rod 7 outwardly and shifting the cut-off 5 to cover outlet z , as in the first instance. This operation is continued 25 so long as pressure is contributed.

It will be readily understood that I do not limit myself to the particular construction herein shown and described, nor do I limit myself to any material or source of energy, for, if desired, where convenient I may employ steam instead of water. 35

Having now described my invention, what I claim is—

In a water-motor, the combination with a main cylinder having a piston therein, and a minor cylinder having also a piston, of a water-chest having an exhaust, ports leading to the main cylinder and the exhaust, a second series of ports leading to the minor cylinder and the exhaust, a cut-off for the main-cylinder ports, a second cut-off for the minor-cylinder ports, connections between the main-cylinder piston and the minor-cylinder cut-off for operating the latter intermittently, and a lever pivoted intermediate its ends and connected with the minor-cylinder piston and the major-cylinder cut-off, whereby the latter may be moved with the minor-cylinder piston. 40 45 50

In testimony whereof I affix my signature 55 in presence of two witnesses.

WILLIAM W. MOYER.
